MELCHIOR ZWICKY, OF BERKSHIRE HEIGHTS, PENNSYLVANIA, ASSIGNOR TO TEXTILE MACHINE WORKS, OF WYOMISSING, PENNSYLVANIA, A CORPORATION OF PENNSYLVANIA

FASHIONING MECHANISM FOR FULL FASHIONED KNITTING MACHINES

Application filed June 4, 1931. Serial No. 542,055.

This invention relates to full fashioned knitting machines, and more particularly to the rod stop and transfer point shifting control mechanisms, my primary object being to provide improved operation thereof whereby the fabric width may be both narrowed and widened to fashion a single continuously knitted blank that can form a complete stocking by a medial longitudinal folding and subsequent seaming together of its side edges.

My improved mechanism and its automatic operation are fully described in connection with the accompanying drawings, and the novel features particularly set forth in the appended claims.

Fig. 1 shows in end view the usual narrowing and stop-nut spindles of a full fashioned knitting machine and embodying my improvements in the operative mechanism therefor.

Fig. 2 is a corresponding rear elevation, showing only the outer end of the spindle and indicating the carrier rods in their relation to the stop nut.

Fig. 3 is a front elevation, on a smaller scale, showing a partial length of the full fashioned machine, and indicating the narrowing rods with their loop transfer points.

Fig. 4 is an enlarged fragmentary view, corresponding with Fig. 3, to more clearly show the narrowing points.

Fig. 5 is a perspective view showing diagrammatically the pawl disengaging mechanism, and the latch for holding it disengaged at the proper time.

Fig. 6 indicates a stocking blank fabric that may be produced with my improved operative mechanism.

Fig. 7 shows a modified form of blank produced by operation of the carrier rod stop nuts alone.

The drawings show portions at one end of a full fashioned knitting machine of known construction, and it is to be understood that duplicate parts at the opposite end operate in a similar manner. The traverse of the series of thread guide carrier rods and the rods carrying the loop transfer points are commonly limited and controlled by screw threaded spindles carrying nuts longitudinal-

ly moved by intermittent rotations of said screws, such varied rod traverse and loop points shifting determining the number of needles supplied with thread and forming loops thereof in the successive courses for the purpose of fashioning the fabric blank in a manner common in the art and well understood.

Referring to the drawings 10 indicates a usual spindle carrying the stop nut 11 for the carrier rods 12; and 15 indicates the so-called narrowing spindle, having as heretofore, reversely threaded portions for nuts 16 and 17 to move in reverse directions their respective rods 18 and 19, carrying transfer points 20, 20.

The spindles 10 and 15 are intermittently turned in known manner by a suitable cam 25 on main cam shaft 26, which acts only when said shaft is shifted longitudinally, to oscillate a lever 27 to which a forked connecting member 28 is pivoted, the spread ends of the latter pivotally engaging link arms 29 and 30 strung upon and radially swingable on the projecting stems of the respective spindles 10 and 15, and said arms carrying pawls 31 and 32 respectively engaging the ratchet toothed wheels 33 and 34 on said spindles. Each spindle is provided as usual with a notched disc 35 and spring pressed detent 36 to accurately position and prevent unintentional turning.

The mechanism above set forth is well known and its operation to fashion the fabric by proper turning of the spindles is as heretofore and requires no further description, such fashioning however being ordinarily a "narrowing" from a maximum starting width to the reduced ankle portion of the stocking blank.

To complete the stocking by continuous knitting, without the heretofore common transfer to another machine, it is necessary to provide for determined widening of the blank to form suitable heel pockets, and to this end I provide an additional gear 40 on spindle 10 with ratchet teeth reversely directed to those of gear 33, and a similar gear 41 on spindle 15, and add pivoted pawls 42 and 43

to the forked connecting member 28, adapted to engage their respective gears 40 and 41.

The mere reversal of spindle 10 by action of pawl 42 on its gear 40 effects a gradually increased traverse of the thread guides, and subsequent reduction of such traverse by action of pawl 31 on gear 33 on said spindle, would produce the heel pockets extensions $m-m$, shown in Fig. 7, and the foot n and toe pocket o continuation as will be readily understood; a fabric blank with unfinished edges being thus simply produced which may form a complete inexpensive stocking.

To produce the preferred fabric blank shown in Fig. 6, which not only has satisfactory selvage edges but transfer marks defining the heel pockets and resembling the usual stocking structure, it is necessary to cooperatively control the intermittent rotations of both spindles 10 and 15 in the special manner which will now be described.

It is to be understood that, as heretofore, each normal racking action of spindles 10 and 15, which takes place only when the main cam shaft is shifted and the knitting action arrested, causes a two needle shift of the rod stops and loop transfer points respectively; that pawl 42 is adapted to reversely rack spindle 10 this same two needle turn, but is disengaged intermittently as later herein will appear; and that pawl 43 has an extension 43^a adapted to cause said pawl to reversely rack spindle 15 only one needle space turn.

As shown pawl 42 is normally tensioned by spring 45 to engage its gear 40, but is moved to disengaging position by a lever 46 pivoted at 47 and having an extension 48 lying in the path of and operated at each reciprocative movement of an extension 49, commonly known as the plaiting bar extension, of the usual slur cock connecting bar operating in known manner the carrier rods 12. A latch device 50 is shown fixedly pivoted at 51, and carrying a pin 52 which is adapted to engage in a notch 53 of an adjustably positioned plate mounted on the stop nut 13, said plate edge normally holding the latch elevated except as the nut reaches the end of its outward travel when notch 53 receives pin 52 to lower latch into engagement with a stud 48^a on lever extension 48 to retain the latter in position to hold pawl 42 disengaged from its gear 40. A duplicate lever and latch at the opposite end of the machine operate in like manner on the duplicate parts there located to hold its corresponding pawl disengaged.

Pawl 43 is tensioned by spring 55 and locked in idle position by a latch 56 engaging a pin 57 on said pawl, said latch being shown as conveniently connected to a pawl 58 not involved in the present improvements.

With the mechanism thus described and pawls 31 and 32 in position to rack their gears 33 and 34 respectively, and pawls 42 and 43 locked in disengaged position, a stocking

blank of usual leg construction may be produced in known manner to the course at the reduced ankle at which it commonly has been transferred to another machine, the heretofore heel tab extension being omitted. At such course indicated by the line $x-x$ in Fig. 6, the pawls 31 and 32 are disengaged and pawls 42 and 43 unlocked so their springs may act to position them to reversely turn the spindles 10 and 15, and by continuing knitting and operating properly the usual dipping of the narrowing head of the machine, the fabric will be widened as shown. In such widening the loop transfer points 20 will move outward instead of inwardly and will leave an intermediate needle free of a loop instead of doubling the loop on certain needles, making the special fashioning lines a and b as shown.

It is apparent that if spindle 15 is racked but one tooth, which is all that is desired for appearances, spindle 10 must not be racked two teeth; also that racking such spindle 10 one tooth would not answer as it would merely move the rod stop away from its rod contact without causing the rod to follow. To overcome this difference in spindle racking the mechanism for disengaging a pawl above described is employed to rack spindle 10 two teeth as heretofore, but only when the carrier rods are at the opposite extreme of this traverse. This is accomplished alternately at each end of the machine, as clearly seen in Fig. 5, by extension 49 of the slur-cock bar disengaging the pawl 42 provided at the end of the machine towards which the carrier rods are moving as the latter approach the end of their traverse against the stops of nut 11, the pawl 42 at the opposite end of the machine remaining engaged and racking its spindle. Latches 50 are set so that when the widening reaches a desired maximum they will function to lock pawls 42 in disengaged position and prevent any further rotation of spindles 10. Also the rounded heel corners c , c may be formed by suitably placed guards 60 acting in well known manner to cover end ones of the needles as the carriers increase their travel to prevent formation of loops thereon.

With the above operation of single notch rotations of each spindle 15 and alternate two notch rotations of spindles 10, the widened loop and increased thread traverse are equalized, but not in the same course, free end loops being formed at each edge in successive courses as will be readily understood, but such loops will not materially effect the selvage edge and they are subsequently secured by the seaming operation. Also any free end loops formed by guard plates 60 will also be secured by the rear seam.

With the mechanism thus fully set forth a stocking blank of proper fashioned shape may be readily produced on a usual knitting machine at one operation without the neces-

sity of transfer and of generally similar appearance to the usual commercial full fashioned stocking. It will also be apparent that the above provision for widening does not in any way effect the usual narrowing operations to fashion the foot and toe portions as well as the leg as heretofore employed.

My improved mechanism is simple, effective, and readily applied to known knitting machine construction at little cost, and adapts such machine for economical production of complete stocking blanks.

The particular mechanism shown and described is a preferred embodiment and modifications thereof may be readily developed that are within the spirit of my invention as defined in the following claims.

What I claim is:

- 20 1. In combination with a full fashioned knitting machine having thread-carrier rods, reciprocative mechanism therefor, and spaced adjustably shiftable stops adapted to limit the reciprocative traverse of said rods, of means for intermittently shifting said stops, means controlled by the rod reciprocative mechanism for alternately preventing shift of each stop, and latch means to prevent shift of both stops at a predetermined position.
- 25 2. In combination with a full fashioned knitting machine having thread-carrier rods, reciprocative mechanism therefor, spaced rotatably mounted threaded spindles, rod stop nuts carried by said spindles adapted to limit the reciprocative traverse of said rods, separate pawl and ratchet gear mechanisms for rotating said spindles, means to jointly actuate said pawls, pawl engaging means actuated by the rod reciprocative mechanism to prevent racking of one pawl at each rod reciprocation, latch devices and means carried by the stop nuts to operate said latch devices to hold said pawls in disengaged positions.
- 30 3. In a full fashioned knitting machine, a thread carrier rod, reciprocative mechanism therefor, a pair of threaded spindles, a carrier rod stop nut mounted on one spindle, a narrowing rod nut mounted on the other spindle, an intermittently operated pawling yoke, a spindle racking pawl for each spindle mounted on said yoke, a disengaging lever for the stop nut spindle pawl, a slide bar actuated by the carrier rod reciprocative mechanism to engage said lever and disengage said pawl at each rod reciprocation, a latch adapted to hold said pawl in disengaged position, and latch operating mechanism carried by said stop nut.

In testimony whereof, I affix my signature.
MELCHIOR ZWICKY.
